Primary Examiner — Elizabeth J Oswecki(74) *Attorney, Agent, or Firm* — HAYES SOLOWAY P.C.(57) **CLAIM**

The ornamental design for a shoe insert, as shown and described.

DESCRIPTION

FIG. 1 is a perspective view of a shoe insert showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a front elevational view thereof.

1 Claim, 4 Drawing Sheets# US D1,082,267 S
